(57) **CLAIM**

The ornamental design for a broom block as shown and described.

DESCRIPTION

FIG. 1 is a perspective view taken from the left and rear side of a broom block in accordance with the new design.

FIG. 2 is a left plan view of the broom block of FIG. 1.

FIG. 3 is a right plan view of the broom block of FIG. 1.

FIG. 4 is a front plan view of the broom block of FIG. 1.

FIG. 5 is a rear plan view of the broom block of FIG. 1.

FIG. 6 is a top plan view of the broom block of FIG. 1.

FIG. 7 is a bottom plan view of the broom block of FIG. 1.

FIG. 8 is a perspective view taken from the left and rear side of a broom block in accordance with a second embodiment of the new design.

FIG. 9 is a left plan view of the broom block of FIG. 8.

FIG. 10 is a right plan view of the broom block of FIG. 8.

FIG. 11 is a front plan view of the broom block of FIG. 8.

FIG. 12 is a rear plan view of the broom block of FIG. 8.

FIG. 13 is a top plan view of the broom block of FIG. 8; and,

FIG. 14 is a bottom plan view of the broom block of FIG. 8.

The broken lines shown in the drawings illustrate portions of the broom block that form no part of claimed design.

1 Claim, 10 Drawing Sheets
